UNITED STATES PATENT OFFICE.

THOMAS LITTLE, OF DETROIT, MICHIGAN.

EYE-SHADE.

SPECIFICATION forming part of Letters Patent No. 733,721, dated July 14, 1903.

Application filed May 9, 1902. Serial No. 106,538. (No model.)

To all whom it may concern:

Be it known that I, THOMAS LITTLE, a citizen of the United States, residing at Detroit, county of Wayne, State of Michigan, have invented a certain new and useful Improvement in Eye-Shades; and I declare the following to be a full, clear, and exact description of the invention, such as will enable others skilled in the art to which it pertains to make and use the same, reference being had to the accompanying drawings, which form a part of this specification.

This invention relates to eye-shades, and has for its object an improved shade to be used for the purpose of protecting the eyes from intense light.

It consists, essentially, of holders similar to the holders of spectacles provided with bows that project over the ears, with a bridge-piece that bends over the nose and with shades which are secured between the bows and the bridge-piece and which are arranged to rest and bear against the forehead and are provided with projections that extend forward to shade the eyes.

In the drawings, Figure 1 is a perspective. Fig. 2 is a front view.

A and B indicate bows, with loops *a* and *b* arranged to loop over the ears of the wearer. C indicates the nose-bridge. Connected to the bows A and B are half-frames 1 and 2, similar to the upper halves of the frame of ordinary spectacles. On each frame-piece 1 and 2 is secured a shade which comprises in each piece a curved shade 3 and a curved bearing-plate 4. The shade 3 is a portion of a cylinder, substantially half a cylinder, with a curved front end 5, and it is joined by a part 4, having a somewhat warped surface that is similar to the section of a cone. The portion of the part 4 that lies between *c* and *d* (see Fig. 2) is cut to correspond with the forehead of a person—that is, a line drawn through *c d e f* would be curved to correspond to the curvature across the forehead just at the line where the forehead meets the eye-sockets—so that when on the forehead of the wearer the pieces 4 and 4 bear with their upper rims against the forehead and prevent an excess of light from entering at that point to affect the eyes. The rims of the parts 4 are preferably thickened or beaded. The sides

of the pieces 3 extend as low as may be necessary to sufficiently protect the eyes, preferably extending to make this part of the shade substantially a half-cylinder.

The piece 3 of each shade meets the piece 4 at an angle, and in use the piece 4 stands approaching a vertical, while the axis of the piece 3 is very nearly horizontal. This brings the edge or rim of the piece 4 entirely above the lower edge of the frontal bone over the eye-socket, where it does not interfere at all with the action of the eyelid.

What I claim is—

1. A device of the character described, comprising independent eye-shades, each shade having a substantially vertically disposed warped bearing-plate the upper edge of which is cut away to conform to the shape of and bear against the frontal bone above and immediately at the side of the eye, a curved shade extending outwardly at an angle from the lower edge of said bearing-plate and means for supporting said eye-shades in position upon the person, as and for the purposes set forth. 65

2. A device of the character described, comprising independent eye-shades, each shade having a substantially vertically disposed warped bearing-plate provided with a beaded upper edge and the upper edge of which is cut away to conform to the shape of and bear against the frontal bone above and immediately at the side of the eye, a shade extending outwardly at an angle from the lower edge of said bearing-plate, a bridge-piece connecting the eye-shades and means for supporting the eye-shades in position upon the person, as and for the purposes described. 75

3. A device of the character described comprising independent eye-shades, each shade consisting of a substantially outwardly disposed shade and a substantially vertically disposed bearing-plate secured to the rear end of said shade and the upper edge of which is cut away to conform to the shape of and bear against the frontal bone above and immediately at the side of the eye, and a connecting member for said eye-shades, as and for the purposes set forth. 90

4. A device of the character described comprising holding-bows, a bridge-piece for the nose, independent eye-shades, each shade consisting of a substantially vertically disposed

warped bearing-plate the upper edge of which is cut away to conform to the shape of and bear against the frontal bone above and immediately at the side of the eye, and a curved shade 5 extending outwardly at an angle from the lower edge of said bearing-plate, as and for the purposes set forth.

5. An eye-shade comprising a substantially vertically disposed warped bearing-plate the 10 upper edge of which is cut away to conform to the shape of and bear against the frontal

bone above and immediately at the side of the eye, and a curved shade extending outwardly at an angle from the lower edge of said bearing-plate, as and for the purposes set forth. 15

In testimony whereof I sign this specification in the presence of two witnesses.

THOMAS LITTLE.
